United States Patent Office.

F. L. KATHAN AND E. D. RUMMER, OF ROSCOE, ILLINOIS.

Letters Patent No. 79,857, dated June 30, 1868.

IMPROVED BOOT-CRIMP.

The Schedule referred to in these Letters Patent and making part of the same.

TO ALL WHOM IT MAY CONCERN:

Be it known that we, F. L. KATHAN and E. D. RUMMER, of the town of Roscoe, county of Winnebago, and State of Illinois, have invented a new and usefully improved "Boot-Crimp;" and we do hereby declare that the following is a full, clear, and exact description of the construction and operation of the same, reference being had to the annexed drawings, making a part of this specification.

Figure 1 represents the boot-crimp, with its devices.

Figure 2 the block and screw.

A A A are the three sections of the crimp, the front and back united by a hinge at B.

C C are the gripes by which the leather is held in place while drying.

D represents the block and screw by which the leather is held, the action of the screw forcing apart the sections of the crimp, and drawing the leather tightly to it, the whole arranged and combined as an article of manufacture.

The advantages of this invention are—

1. The leather is not cut with tacks, which are required, in the old process, to hold it fast.
2. The use of a hammer is dispensed with, which saves the leather from still further injury.
3. The wrinkles are always drawn out, and the leather does not "full up" on the instep.
4. The leather is ready for use in two minutes, while, by the old process, three hours are sometimes required to so prepare it.

What we claim as our invention, and desire to secure by Letters Patent, is—

The combination of the hinged crimp A A A, block and screw D, with the gripes C C C, when arranged, constructed, and operating as herein described, and for the purposes as set forth, as an article of manufacture.

F. L. KATHAN,
E. D. RUMMER.
